Primary Examiner — Mark A Goodwin

(74) Attorney, Agent, or Firm — Novick, Kim & Lee,
PLLC; Jae Youn Kim; Hyun Woo Shin(57) **CLAIM**We claim the ornamental design for an electric outlet cover,
as shown and described.**DESCRIPTION**FIG. 1 is a perspective view of an electric outlet cover,
showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings show portions of the
electric outlet cover that form no part of the claimed design.**1 Claim, 6 Drawing Sheets****FIG. 1**

FIG. 2

FIG. 3

FIG. 4

FIG. 5

FIG. 6
